UNITED STATES PATENT OFFICE.

HERMAN L. MEYER, OF ST. LOUIS, MISSOURI.

DESIGN FOR A PICTURE-FRAME.

SPECIFICATION forming part of Design No. 36,477, dated August 4, 1903.

Application filed June 27, 1903. Serial No. 163,439. Term of patent 14 years.

To all whom it may concern:

Be it known that I, HERMAN L. MEYER, a citizen of the United States, residing at and whose post-office address is No. 3322 Oregon 5 avenue, in the city of St. Louis, State of Missouri, have invented a new and original and ornamental Design for Picture-Frames, which design is illustrated in the accompanying drawing, which is a front elevational view of 10 a picture-frame made in accordance with my new design.

What I claim is—

The ornamental design for a picture-frame, as herein shown.

In testimony whereof I have signed my 15 name to this specification, in the presence of two subscribing witnesses, at St. Louis, Missouri, this 20th day of June, 1903.

HERMAN L. MEYER.
